8 Claims. (Cl. 250—36)

The present invention relates in general to electronic musical instruments, and in particular to an audio oscillator tone generating circuit which is adapted to play selectively, any one of a plurality of single musical frequencies.

Such a circuit is desirable for purposes of economy, if the instrument is to be a solo instrument, where it will never be required to play more than one note at a time. There are at least two applications where a musical instrument of this type is useful. One is in a solo instrument intended for example, for playing the melody only, while the accompaniment is played on some other instrument such as the piano or organ. Another application is in an instrument intended to supply the pedal bass notes for an electronic organ.

For either of these cases a single oscillator according to the present disclosure, can be designed to operate over a frequency range of at least an octave. A plurality of switches operable by means of the keyboard of the instrument, are connected in a sequence circuit, making possible the selective playing of any one of the required musical notes.

It is required first to provide an audio oscillator having good frequency stability, and approximately constant output voltage over the frequency range required. A second requirement is that of providing an economical and practical, individual tuning means for each of the notes to be generated by the oscillator.

The first requirement is met by the use of the conventional two stage oscillator, using a parallel tuned circuit. The second requirement is met by the use of inexpensive potentiometers, which serve as the individual tuning means.

It is therefore an object of this invention to provide an economical tuning means in a multi-frequency oscillator circuit.

Another object is to provide a two stage oscillator whose voltage output is reasonably constant over a wide frequency range.

Another object is to provide means for using a variable resistance to vary the effective capacitance in a parallel resonant circuit, without appreciably affecting the Q of the circuit.

Another object is to provide a circuit which employs lower cost capacitors than would otherwise be needed.

Briefly, in accordance with the invention a tone generating circuit for use in an electronic musical instrument is provided in which an oscillator circuit generates a wave of a selectable frequency in accordance with the amplitude of a wave derived from the oscillator which is applied to a capacitor connected in a frequency determining circuit. Through the provision of a low impedance source for the wave applied to the capacitor, the Q, i.e. efficiency of the frequency determining circuit remains high. In an exemplary embodiment the capacitor receives a wave

2

derived from a low impedance source provided by a cathode resistor associated with an electron tube and the amplitude of the wave applied to the capacitor is selectable by key actuated switches to determine the frequency of oscillation.

Other objects will appear from the following description, reference being had to the accompanying drawing in which the single figure is a schematic circuit drawing, illustrating a preferred embodiment of the invention.

- 10 The drawing shows two triode electron tubes 1 and 2 connected in a two stage oscillator circuit. In this arrangement the plate terminal of triode 1 is connected to the grid of triode 2 through coupling capacitor 6 and resistor 8. The reactance of capacitor 6 should be smaller than the resistance of resistor 8 at the lowest frequency required of the oscillator. The plate terminal of triode 2 is connected to the grid of triode 1 through the network comprising coupling capacitor 12, resistor 10, and resistor 11 in series, and shunt capacitor 7. A parallel resonant circuit comprising inductor 3 and capacitor 4 the access terminals of which are connected together between the grid terminal of triode 1 and the common ground return. This inductor may be of the iron core type, and should have a Q of 5 or higher. Plate coupling resistors 9 and 13 supply plate voltage to the triodes from the B plus supply. The cathode terminal of triode 1 returns to the common ground return through resistor 5. The cathode terminal of triode 2 returns to ground through a plurality of parallel connected tuning potentiometers 14, 15, 16. A sequence switching circuit is shown, comprising three sets of switches. The switch arm 20 of the first switch is connected to the resonant circuit and the grid of triode 1. The switch arm 23 of the second switch is connected to the back contact 21 of the first switch 20. The switch arm 26 of the last switch is connected to the back contact 24 of the second switch 23. The last switch 26 has no back contact. The back contact of each switch is normally closed to the switch arm. Each switch has a normally open front contact. Front contact 22 is associated with switch 20, contact 25 with switch 23, and contact 27 with switch 26. Tuning capacitor 17 is connected from contact 22 to the movable contactor of potentiometer 14, capacitor 18 from contact 25 to potentiometer 15, and capacitor 19 from contact 27 to potentiometer 16.

Coupling capacitor 28 and resistor 29 provide means for taking output signal voltage from the oscillator circuit. Switches 30, 31, and 32 are arranged to selectively connect the output voltage at capacitor 28 to an amplifier 33. The output of the amplifier is connected to loud speaker 34. Switches 30, 31, and 32 are all wired in parallel so that the closure of any switch connects the oscillator output signal to the amplifier. These switches are mechanically arranged to be operated simultaneously with switches 20, 23, and 26, by means of the playing keys of the instrument. Thus switch 30 operates with switch 20, switch 31 with switch 23, and switch 32 with switch 26.

Although only three sets of switches and tuning components are illustrated, it should be understood that twelve sets, together with their appropriate playing keys would be provided, if a range of one chromatic octave is required.

65 The circuit operation is as follows. The signal from the plate of the first triode overdrives the grid of triode 2, so that triode 2 is limiting. Reasonable changes in the output voltage from triode 1 will therefore cause no change in the output voltage from triode 2. The signal

voltage from triode 2 is brought through blocking condenser 12 and resistors 10 and 11, back to the grid of triode 1, and the tuned resonant circuit. The circuit oscillates at the resonant frequency of the inductor 3 and the capacitor 4 in parallel. Assuming in one case that the capacitance of condenser 7 is zero, the values of resistors 10 and 11 are selected to considerably attenuate the signal voltage appearing at the grid of triode 1. Triode 1 must operate linearly and without distortion. The amplitude of the feedback signal voltage, and the cathode resistor 5 are selected to meet this requirement. Their values are not critical. The circuit thus oscillates even though no playing keys are depressed, but since none of the switches 30, 31, or 32 are closed, no signal reaches the amplifier and loudspeaker.

The operation when a playing key is depressed is as follows. A set of switches is operated by the key, as for example switches 20 and 30. Switch arm 20 breaks from contact 21 and makes to contact 22, thus connecting capacitor 17 to the resonant circuit. This lowers the frequency of oscillation to a new value, which is determined by the apparent capacitance of condenser 17 in parallel with the resonant circuit. The potentiometer 14 provides the tuning means for adjusting the apparent capacitance of condenser 17. When the movable contactor arm of the potentiometer tuning control is turned to its limit at the ground end of rotation, the apparent capacitance of capacitor 17 is its actual capacitance. When the contactor arm is turned to its opposite limit at the cathode end of rotation, the apparent capacitance of condenser 17 is considerably greater than its actual value, and the frequency of oscillation is lowered still further. A gradual change in capacitance and frequency occurs as the tuning control 14 is rotated from one limit to the other. An effective and economical tuning means is thus provided for the oscillator.

There is a sequence of operation of switches 20 and 30, when their associated playing key is depressed. Switch arm 20 closes to contact 22 before switch 30 closes. This is required so that the oscillator will have changed to its new frequency before the output signal is connected to the amplifier and loudspeaker. The reverse order holds when the key is released, and therefore the only pitch heard from the speaker is that selected by the tuning adjustment of potentiometer 14.

The same principle of operation applies to the other switching and tuning circuits in the sequence. Thus if the key associated with switches 23 and 31 is depressed, the only pitch heard from the speaker will be that which is determined by the value of capacitor 18 and the adjustment of tuning control 15. Switches 20, 23, and 26 are connected in sequence so that if two keys are depressed simultaneously, the correct pitch of only one of the notes will be heard from the speaker. Thus for example, if switches 20 and 23 are both operated, only the pitch controlled by switch 20 will be heard, because switch arm 20 in operating, moves away from back contact 21. This opens the circuit to switch 23, thereby making it ineffective.

The values of capacitors 17, 18, and 19 should be selected so that with their respective tuning controls set to approximately mid-rotation, each associated playing key will play one of three selected consecutive chromatic notes. Thus with twelve sets of keys, switches, and tuning means, one oscillator may be made to generate selectively, any one of twelve individually tunable chromatic notes.

To explain the manner in which the tuning means operates, consider that switch 20 is operated, and that at a given instant in a cycle of oscillation, the grid end of the resonant circuit is moving in a positive direction, relative to the grounded end. The positive swing is charging capacitor 4 at a rate determined by its capacitance value. This is also true of capacitor 17, if tuning control 14 is set at the grounded limit of its ro-

tation. But assume that the tuning control is set to the opposite limit. Capacitor 17 now connects to the cathode of triode 2 instead of to ground. At the given instant, since the grid of triode 1 is swinging positive, its plate is swinging negatively. Therefore the grid and cathode of triode 2 are also swinging negatively in the fashion of a cathode follower. The voltage change at the cathode of triode 2 is thus in the opposite phase to that at the grid of triode 1, and is of considerably greater amplitude due to the voltage gain of triode 1. The rate at which capacitor 17 is now charging is thus considerably increased. Similarly its apparent capacitance is considerably increased. The frequency of oscillation is therefore lowered when the tuning control is set to the cathode limit of rotation, since the apparent capacitance across the tuned circuit has been increased. This is therefore the low frequency limit of the tuning control. As the control is rotated toward its opposite limit the frequency is gradually increased. The ground limit of rotation is therefore the high frequency limit of the tuning control. Using the circuit constants given herein, full rotation of the tuning control will provide approximately a twenty percent frequency change.

The circuit of Figure 1 effectively multiplies the actual value of capacitor 17 by a factor of approximately 6, when using 6J5 tubes. This makes possible the use of lower cost condensers, since the cost varies with the capacitance value.

It should be understood that while two separate triode tubes are shown in the oscillator of the drawing, a single duo-triode such as the 6SN7 will operate equally well. Other suitable oscillator circuits may be provided by one or more electron tubes or transistors suitably connected.

In order to avoid introducing too much resistance across the tuned circuit and thereby lowering its Q, when control 14 is set near its mid-position, the resistance of the control should be kept reasonably low. If there are twelve controls connected in parallel, their combined resistance value must also serve as an adequate cathode resistance for triode 2. If the twelve controls each have a resistance value of 25,000 ohms, their combined resistance is 2,100 ohms which is a satisfactory cathode resistance for triode 2. It will be found that this value of control resistance will not affect the Q of the tuned circuit to a harmful degree. Accordingly, a feature of substantial advantage of my invention is the control of the frequency of an oscillator without excessively loading or lowering the Q of the frequency determining circuit.

As previously stated triode 2 is over-driven so that it is distorting. The output signal amplitude therefore does not change perceptibly over the full range of an octave. Also this signal is rich in harmonics, and is identified herein as reed type tone color.

If it is desired to take flute tone also from this oscillator, a connection can be made to point 35. Another set of switches (not shown) similar to those at 30, 31, and 32 would be required to conduct the flute tone signal from point 35 to the amplifier. In order to hold the flute signal amplitude constant over an octave range, a shunt capacitor 7 may be utilized. This capacitor may be selected, together with the values of resistors 10 and 11, to form a low pass filter, so that the feedback signal voltage appearing at the grid of triode 1 remains at essentially constant amplitude over an octave range. Without the low pass filter, the feedback signal voltage appearing across the tuned circuit rises as its impedance rises, when the frequency is increased. This capacitor thus serves also to eliminate the possibility of over-driving triode 1 at the higher frequencies of oscillation. The phase shift introduced by capacitor 7 does not seem to be detrimental to the frequency stability of the oscillator.

I am aware of many applications of the oscillators in the prior art, and of the use of feedback in numerous forms, and of the use of a variable resistor in series with a capacitor for phase and frequency adjustment, but I am not aware of the prior combination of an oscillator whose frequency may be selectively adjusted using fixed capacitors and adjustable resistors, in a circuit which does not lower the Q of the oscillator circuit.

Although for the purpose of illustrating and describing the invention a certain preferred embodiment has been shown, it will be apparent to those skilled in the art that various modifications can be made, such as the use of other oscillator circuits, without departing from the basic principles of the invention, I therefore do not wish to be limited to the precise details set forth herein, but desire to include within the scope of the invention those modified forms by means of which similar results may be obtained in substantially the same way. For example, throughout the specification and claims, various current flow control devices have been designated as electron tubes including a plate, grid and cathode. It is intended that the designation include any equivalent arrangements such as a transistor circuit in which there is included either a junction or point contact current flow control device having a current collector, a current emitter and a control element such as a base.
